UNITED STATES PATENT OFFICE

172,297

SPREADER FOR LOOSE-LEAF LEDGERS

Foster Cloud Nixon, Apollo, Pa.

Application June 11, 1953, Serial No. 25,452

Term of patent 14 years

(Cl. D74—1)

To all whom it may concern:

Be it known that I, Foster Cloud Nixon, a citizen of the United States and a resident of Apollo, State of Pennsylvania, have invented a new, original, and ornamental Design for a Spreader for Loose-Leaf Ledgers, of which the following is a specification, reference being had to the accompanying drawing, forming a part thereof.

Figure 1 is a perspective view of a spreader for loose-leaf ledgers, showing my new design;

Figure 2 is a side elevational view of the same;

Figure 3 is a front elevational view of the same, and

Figure 4 is a bottom plan view thereof.

I claim:

The ornamental design for a spreader for loose-leaf ledgers, as shown.
